G. R. WELCH

VAPORIZER

Filed July 24, 1924

FIG. 1

FIG. 2

INVENTOR.

George R. Welch

BY

Stanley M. Udale

ATTORNEY.

UNITED STATES PATENT OFFICE.

GEORGE R. WELCH, OF DETROIT, MICHIGAN.

VAPORIZER.

Application filed July 24, 1924. Serial No. 727,891.

This invention relates to an improved vaporizer.

It refers specifically to an improvement upon my copending application, Serial No. 5 694,995, filed Feb. 25th, 1924.

In that application an inlet manifold is shown with a dependent connecting passage connected to the outlet ports so as to collect unvaporized fuel, and an exhaust manifold 10 cast integral with said dependent passage for the purpose of vaporizing the fuel therein. Such a device works excellently under all conditions of speed, load, and throttle position except at extreme idle, when there is a 15 tendency for the mixture to be variable and the running of the engine consequently is irregular.

The object of this invention is to more positively vaporize the fuel charge when 20 running under such conditions. That is to say, when running at the lowest possible idling speed. An additional object is to provide means for cleaning the interior surfaces of the dependent passage.

25 Figure 1 shows a cross sectional elevation on the plane 1—1 of Figure 2.

Figure 2 shows the elevation of the inlet and exhaust manifolds.

In Figures 1 and 2, A is the inlet manifold, B is one of the inlet ports leading to the inlet valve (the corresponding inlet port to the left is not shown). C is the dependent passage connecting the port B with the corresponding inlet port (not shown). D is a 30 cover plate for rendering the dependent passage C accessible for the purpose of cleaning. E is the exhaust manifold cast integral with the dependent passage C. F, G, and H are exhaust outlets leading to the exhaust manifold E. I is the butterfly throttle in the entrance to the inlet manifold A. J is the throttle shaft. K is a bypass located immediately above the throttle valve I. L is a 35 tube cast integral with the inlet manifold and leads to the middle of the dependent passage C so that there is a bypass from the mixture entrance around the throttle valve I, through the dependent passage C, and into the inlet outlet B and to the inlet outlet not shown.

As is well known, when a hydro-carbon fuel is heated more or less carbon is deposited due to the obscure chemical phenomenon

known as "cracking". This carbon although a conductor of heat is a very much poorer 55 conductor of heat than is cast iron, of which these manifolds are made. The result is that the vaporizing effectiveness is reduced by at least one-half.

It follows, therefore, that the surfaces of 60 the vaporizer should be cleaned from time to time depending on the miles run, the quality of the fuel, and the load conditions.

Operation.—When the engine is running slowly it is obvious that the entire charge of 65 both air and fuel is bypassed around I, through the bypass K and L, into the dependent passage C, and that the fuel is therefore subjected to the full force of the exhaust passing out of the exhaust manifold E. 70 Thoroughly vaporized fuel therefore reaches the inlet outlet B and the low speed operation of the carburetor is satisfactory.

When the throttle is opened this vaporizer functions exactly as the vaporizer described 75 in my co-pending application referred to above. That is to say, an explosive mixture enters the mixture entrance past the manifold A, past the throttle I, divides in the inlet manifold, and the unvaporized fuel 80 runs down the walls of the inlet manifold A and is caught and collected in the dependent passage C, wherein it is thoroughly vaporized by the exhaust gases in E.

The cleaning operation is easily conducted 85 by merely removing the cover plate D and exposing the walls of the dependent mixture passage C.

What I claim is:

In a vaporizer for an internal combustion 90 engine, the combination with an exhaust manifold of an inlet manifold forming a loop and having a dependent fuel and air mixture passage forming an unrestricted return path located in heat conducting relationship with 95 said exhaust manifold, a mixture entrance to said inlet manifold, a throttle valve therein, a bypass around said throttle discharging into said dependent passage, whereby when the throttle is closed the explosive mixture necessary to operate the engine at idling 100 speed is drawn through said dependent passage and vaporized therein.

In testimony whereof I affix my signature.

GEORGE R. WELCH.
